UNITED STATES PATENT OFFICE

HEYMAN ROSENBERG, OF NEW YORK, N. Y.

DESIGN FOR A SCREW BOLT OR SIMILAR ARTICLE

Application filed May 13, 1932. Serial No. 43,792. Term of patent 14 years.

To all whom it may concern:

Be it known that I, HEYMAN ROSENBERG, a citizen of the United States, residing at New York city, in the county of New York and State of New York, have invented a new, original, and ornamental Design for Screw Bolts or Similar Articles, of which the following is a specification, reference being had to the accompanying drawing, forming part thereof.

Figure 1 is a plan view of the article showing my new design.

Figure 2 is an edge view thereof, and

Figure 3 is a central, cross section therethrough.

The article is a complete, integral article of manufacture made and sold as such, and the ornamentation at the end of the screw bolt is the dominant feature of the design.

I claim:

The ornamental design for a screw bolt or similar article, substantially as shown and described.

HEYMAN ROSENBERG.
